Fig. 3.

To all whom it may concern:

Be it known that we, Alfred W. Madl and Joseph A. Hill, citizens of the United States, residing at Milwaukee, in the county of Milwaukee and State of Wisconsin, and Glen Ellyn, in the county of Du Page and State of Illinois, respectively, have invented a new, original, and ornamental Design for a Household Mixer, of which the following is a specification, reference being had to the accompanying drawings, forming a part thereof.

Figure 1 is a front perspective view of a household mixer, showing our new design;

Figure 2 is a rear perspective view thereof; and

Figure 3 is a fragmentary longitudinal cross section taken through the rear portion thereof.

The outline of a pair of agitators shown in broken lines in Figures 1 and 2 is for illustrative purposes only.

We claim:

The ornamental design for a household mixer, as shown and described.
